ABSTRACT: A garment hanger having a frame with adjustable shoulder supports thereon adapted to hold any size of a man's suit, coat, or ladies' fur coat, or the like. The hanger comprises an ordinary garment hanger embodying a vertically disposed member in the longitudinal center thereof, the upper end of the aforesaid vertically disposed member terminating in a hook, while two opposed and angularly disposed supporting members extend outwardly and downwardly from the lower end of the said vertically disposed member, the outer end of each supporting member terminating in a vertically disposed end member having its lower end supporting a horizontally disposed cross member having a convex upper surface. Each of the two supporting members has an outwardly and downwardly inclined shoulder supporting member a convex upper surface and internal structure which fits over the two supporting members of the garment hanger. Each of the supporting members is provided with a thumb screw to firmly hold the shoulder supporting member in any longitudinal position on the two supporting members, thereby permitting the hanger to be adjustable to hold any size of garment in a way that will prevent the wrinkling of the same.

PATENTED DEC 22 1970

FIG. 1

FIG. 2

FIG. 3

FIG. 4

INVENTOR
ROY W. CAMPBELL

ADJUSTABLE GARMENT HANGER

From the above statement, it will be seen that this invention relates to hangers, and more particularly, to hangers adapted to hold nearly any type of garment having sleeves.

It is the principal object of this invention to provide an adjustable garment hanger that can, as its name implies, be adjusted to firmly hold any upper garment merely by the adjusting of two thumb screws that are so located as not to interfere in any way whatsoever with the support of the garment placed on the hanger.

Another object of this invention is to provide an adjustable garment hanger of the character herein described that can be manufactured from nearly any coat hanger by the addition of the two herein described longitudinally disposed members.

Still another object of this invention is to provide an adjustable garment hanger of the character herein described that can be mass produced at low retail cost from nearly any desired material, such as wood, metal, plastic or the like, or the combination of any two or more materials of any desired color.

Other and further objects and advantages of this invention reside in the novel structures and arrangements hereinafter more fully described in this specification and appended claims, and illustrated in the accompanying drawing in which:

FIG. 1 is a perspective view of this invention.

FIG. 2 is a longitudinally disposed sectional view of this invention, taken along line 2-2 of FIG. 1, and viewed in the direction indicated by the arrows.

FIG. 3 is a perspective view of one of the longitudinally disposed members of this invention, rotated to show the internal structure of the same.

FIG. 4 is a sectional view of this invention, taken along line 4-4 of FIG. 2, and viewed in the direction indicated by the arrows.

In the several views of this invention, like parts of the garment hanger are indicated by like reference numbers.

The reference number 5 indicates the adjustable garment hanger in its entirety.

Directing ones attention first to FIG. 2 of the accompanying drawing it will be seen that this invention 5 consists of a typical garment hanger or frame 6 which, in this instance, is provided with a frustum shaped collar 7, a longitudinally disposed bottom member 8, and a convex upper surface 9. The aforesaid hanger 6 is provided with two opposed downwardly and outwardly inclined members 10 that are identical in structure. Each member 10 is actually a shoulder supporting member. Each member 10 embodies garment shoulder supporting member 11 each of which has a convex upper surface and a concave lower surface and two equally spaced and parallel rectangular members 12 that are centrally located within the aforesaid concave portion of said garment supporting member 11, as is clearly shown in FIG. 3 of the accompanying drawing. The two members 12 are adapted to fit over the top of the downwardly and outwardly inclined members 13 of the garment hanger 6. The member 13 is preferably rectangular in cross section, although it can be of any desired shape. A downwardly extending lug 14 is integrally formed with each of the members 12 in order to provide a support for the thumb screw 15 that firmly holds the member 10 in any desired position along the member 13 of the garment hanger 6, as one can see and understand upon examination of FIG. 2 of the drawing. Each of the aforesaid members 10 is provided with an

outer plate 16 as well as a plurality of equally spaced gusset plates 17 that are located inside the convex garment supporting member 11 in order to support the two aforesaid members 12 of this invention.

Looking now at FIGS. 1 and 2 of the accompanying drawing it will be seen that the just described longitudinally disposed member 10 is basically the same length as that of each member 13 of the garment hanger 6. It will also be noted on examination of the drawing that the inward end of each member 10 slidably fits into suitable openings in the lower portion of the slanting surface 18 of the aforesaid collar 7 which may or may not be hollow depending upon the detail construction of this part of the invention.

It is to be fully understood that should each of the aforesaid longitudinally disposed members 10 be made integral with all of the related structure contained within the aforesaid convex member 11, this portion of the invention, that is illustrated in FIG. 3 of the accompanying drawing, can be molded plastic or the like.

It is realized from reading the above description of the construction of this invention of an adjustable garment hanger and examining the accompanying drawing, that all one has to do to make the hanger support a sleeved garment of any size, is to loosen the two thumb screws 15 and then slide the two aforesaid members 10 outward (or inward, if already in an outward position) to the desired length as suggested by the phantom lines in FIG. 2, and then tighten the same two thumb screws 15.

This invention of mine can be manufactured as an entirely new adjustable garment hanger, or it can be produced by modifying and adding structure to existing garment hangers, as will be understood by those experienced in the art.

The invention is subject to any and all changes in configuration, detailed design, and/or modifications that one may care to make in the same in so long as the changes and/or modifications fall within the scope and intent of the appended claims.

I claim:

1. An adjustable garment hanger, including a frame member having its upper end terminating in a hook adapted to support the garment hanger, two support members of said frame secured and extending in downwardly and outwardly opposed directions from said hook, a frustum shaped collar below said hook covering the inner ends of said two support members, two elongated shoulder supporting members having convex upper surfaces and concave lower surfaces slidably received over said two support members, two centrally located, equally spaced and parallel rectangular members within each concave portion, said rectangular members secured to and extending longitudinally of the concave portion, one on each side of a hanger member, opposed lugs secured to and extending downwardly from adjacent rectangular members and thumb screws extending through adjacent lugs adjustably securing said rectangular members to said two support members.

2. The invention of claim 1 wherein an outer plate is secured to the outer end of each shoulder supporting member and spaced gusset plates extend from the concave portions to the rectangular members and securing them together.

3. The invention of claim 1 in which said frustum shaped collar has opposed openings about permitting the inner ends of the shoulder support members to slide into said frustum shaped collar.
